UNITED STATES PATENT OFFICE

ALEXANDER NYMAN, OF NEW YORK, N. Y., ASSIGNOR TO DUBILIER CONDENSER CORPORATION, OF NEW YORK, N. Y., A CORPORATION OF DELAWARE

ALTERNATING CURRENT OPERATED RADIO SET

Application filed February 26, 1926. Serial No. 90,807.

My invention relates broadly to alternating current actuated radio receiving apparatus and more particularly to a circuit arrangement whereby the present commercial designs of receiving sets employing electron tube amplifying systems can be readily changed so that the tube circuits may be effectively energized by electric power derived from the usual alternating current lighting source.

One of the objects of my invention is to provide means whereby existing constructions of radio receiving sets employing electron tube amplifiers may be operated without interference from hum of alternating current supplied from the usual commercial alternating current house lighting system.

Another object of my invention is to provide a radio receiving system with detector means which does not require the supply of alternating current or voltage and which is not detrimentally affected by the alternating current characteristics of the power supply.

25 A further object of my invention is to provide a detector system for the signaling energy of an alternating current operated radio receiver which is not influenced by the hum of the alternating current power supply but which functions to rectify the incoming signaling energy.

Still another object of my invention is the provision of a photo-electric cell as a detector element in an alternating current operated radio receiving apparatus.

With these and other objects in view as may hereinafter appear, my invention consists in the combination of certain constituent members into a composite radio receiving circuit which will be fully described and claimed, with the understanding that the several necessary elements comprising my invention may be varied in construction, proportion and arrangement, without departing from the spirit and scope of the appended claims.

In the drawings, Figure 1 is a diagrammatic plan showing the circuit arrangement of an alternating current operated radio re-

ceiving set embodying the principles of my invention;

Fig. 2 is a schematic plan view showing the circuits heretofore employed in a multi-tube, tuned radio frequency battery actuated radio receiving set; and

Fig. 3 shows a regenerative receiver system embodying the principles of my invention.

The same numerals and symbols have been used to identify the same parts throughout the several views.

Actuation of radio receiving sets from an ordinary 60 cycle house lighting supply circuit is productive, as is well known, of a very pronounced disturbing hum that generally is not only very disagreeable to listen to, but also prevents the intelligent reception of the received signals, either spoken words or musical sounds. Therefore, batteries have been found up to the present to be the most practical, reliable and noiseless source of power for energizing the filaments and the plate circuits of the various vacuum tubes serving as amplifiers or detectors in the receivers in ordinary use. Although battery actuated radio sets admittedly are capable of quiet reception, nevertheless, the reliability of the battery cells is far from being infallible, for their active length of life is usually short, owing to the occurrence of internal chemical action even when no current is being drawn from the cells, hence, frequent recharging or rather costly replacement of cells is necessary and causes general dissatisfaction.

The ability to dispense with all batteries in radio sets and employ an ever-present power source instead, is of great advantage and various inventors have devised more or less complicated methods and means whereby an A. C. supply may be applied to certain radio sets with a fair degree satisfaction. While it has been found feasible to employ alternating current directly applied to all the filaments of the tubes of the set except that of the detector tube, usually the filament of the latter is supplied with heating current by a battery of suitable voltage, or the triode tube detector is replaced by some form of crystal detector; for, when a triode electron tube is used as a detector there

is impressed on both the plate and the filament a 60 cycle alternating current voltage, which though sometimes small, becomes very objectionable when amplified by one or two stages of audio frequency amplification. 5 With the more or less unstable crystal detector no 60 cycle alternating current is required for heating a filament, nor is there present a plate to which alternating current voltage is supplied. 10

I have discovered that a photo-electric cell when exposed to light rays will serve as a stable detector of the signaling current without interference from the alternating hum. 15 I therefore provide an electron tube amplifying system at the receiver with a photo-electric cell interposed in the system for deriving uni-directional currents from the incoming signaling energy which may be further amplified through an electron tube system which 20 is supplied with power from an alternating current lighting source without interference from the alternating current hum in the responsive device which is actuated by the amplifying system. 25

Referring more particularly to Figure 1 of the drawings the numeral 1 indicates an antenna system forming a radio frequency oscillating circuit which is connected to ground at E. Triode vacuum tubes 2 and 3, and high frequency transformers T_1 , T_2 , T_3 , constitute a high frequency amplifying system connected with the radio frequency energy collecting circuit. Tubes 4 and 5 and audio frequency transformer T_4 constitute the audio frequency amplifying elements of the receiving set to which the customary head phones 6 or in lieu thereof, some form of loud speaker, are connected in the plate circuit of tube 5. Power for the filaments of tubes 2, 3, 4 and 5, is supplied from the low voltage secondary of the step-down transformer T, whose primary winding is connected to the standard source of alternating current power supply. The filament leads 7, 7' of tubes 2, 3, 4, 5, are connected in parallel across the common leads 8, 9, which are respectively connected with transformer terminals 10, 11, shunted by a non-inductive balancing resistance 12 with a centrally located slider 13. Plate current for the triode tubes of the set is supplied also from the A. C. mains by any suitable rectifier S, preferably one of the vacuum tube type, which is interposed between the A. C. mains and common leads 14, 15, connected in the plate circuits of the tubes 2, 3, 4, 5. In practice, filament transformer T and rectifying outfit S may be suitably mounted within a protected container or case, that is, provided with the requisite terminal binding posts for making the correct connections to the set. Adjustable contact 13 or the slider of balancing resistance 12, is connected to the negative lead 14 of rectifier S by wire 16. By suitably adjusting the posi-

tion of slider 13 on resistance 12 the normal voltage of the grids is kept at a steady value with respect to the average voltage of the electrical midpoint of the filaments thus eliminating any hum which variations of the grid voltage would cause. 70

Between the radio and the audio stages composing the receiving set, photo-electric cell PC is interpolated into the circuit in such fashion that the grid electrode 25 receives the output energy of T_3 . Sensitive plate 17 of light cell PC is electrically connected to grid 18 of audio frequency amplifying tube 4 by conductor 19, to which one terminal of a non-inductive resistance 20, is also connected. Terminal 21 of resistance 20 is connected by lead 22 to one end of the secondary winding of audio transformer T_4 . Resistance terminal 21 is likewise directly connected to lead 14 or preferably, to a terminal of a biasing battery C, which may be interpolated between 21 and 14. Positioned between the photo-electric cell PC and facing plate 17 thereof, miniature bulb B' is employed to steadily illuminate cell PC with light of the proper intensity, thereby causing the space between the plate 17 and grid 25 of tube PC to become conductive to the desired degree. The luminous filament of bulb B' is supplied with A. C. power by transformer T through conductors 8 and 9, to which the leads of this filament are connected. Since photo-cell PC permits only the flow of uni-directional current, whose intensity varies according to the voltage applied to the grid and plate of the cell, which is continually subjected to the steady illumination of the adjacent but separate bulb B', high frequency voltages applied to the grid of cell PC by the secondary of transformer T_3 produce a uni-directional flow of current of varying intensity through the cell PC which current is passed on to the audio amplifiers 4 and 5 and thus to the phones 6 or other variety of indicator. Photo-cell PC, therefore, performs the function of a detector, which in contrast with the usual triode detector contains no self-contained hot filament that gives rise to disturbances when it is supplied with alternating heating current. In practice, light cell PC is so constructed that it can be inserted into the socket ordinarily occupied by the usual triode detector tube. Luminous bulb B' is mounted in a suitable socket and container which may be located in proximity to PC in any convenient manner so that the hot cathode 26 tends to subject the photo-electric cell to a combination of light rays. 115

In Figure 2 I have shown the usual battery actuated receiving set employing tuned radio frequency amplification as in the case of Fig. 1, and a detector tube 27 connected to a two stage audio frequency amplifier constituted by tubes 4 and 5 and transformers T_4 and T_5 . Filament batteries A and plate 125

batteries B replace in Fig. 2 the A. C. transformer T, and the A. C. rectifying and smoothing outfit S of Fig. 1. Particular connections necessary for the installation of light bulb B' and detector photo-cell PC in place of the triode detector 27 of Fig. 2, are clearly indicated in Fig. 1 and the diagrams represent the departure necessary from the battery operated set in order to excite the tube circuits from alternating current. That is to say, electron tube detector 27 is substituted by the photo-electric cell PC and light bulb B' when the supply system is changed over from batteries to the alternating current source.

In Figure 3 of the drawing I have illustrated a regenerative form of detector circuit constituted by the photo-electric cell PC having an additional electrode 28 therein connected through an inductance 29 to the input of a transformer system T₂ which connects to the two stages of audio frequency amplification. The inductance 29 couples with inductance 30 in the antenna circuit enabling an increased amount of rectified signaling energy to be passed to the amplification system. The bulb B' is continuously energized for rendering the photo-electric cell conductive to uni-directional current.

The three electrode photo-electric cell shown in Figure 3 can very advantageously be employed in the circuit shown in Figure 2 by substituting it for the middle vacuum tube which has the plate 27. This photo-electric cell will be so connected that the plate 17 will take the place of the heated filament, the grid 25 will be connected in the usual way to one terminal of the secondary of a transformer T₂, and the grid 28 will take the place of the plate 27 with the coil 29 arranged to cooperate with the transformer T₁.

While I have shown and described the preferred form of my invention I wish it to be understood, that I do not confine myself to the precise details of construction as herein set forth by way of illustration, as it is apparent that various changes may be made therein by those skilled in the art without departing from the spirit of the invention or exceeding the scope of the appended claims.

What I claim as new and desire to secure by Letters Patent of the United States is as follows:

1. In a signal receiving apparatus, means for connecting said apparatus to a source of alternating current, a plurality of amplifying devices each having an electron emitting element, a photoelectric detecting device having an electron emitting element and means and means for energizing all of said electron emitting elements through said connecting means.

2. Signal receiving apparatus comprising a plurality of electron discharge tubes having heatable electron emitting cathodes, said

tubes being adapted to amplify signaling currents, a photoelectric cell having a light sensitive electrode therein, said cell being adapted to rectify signaling currents, a lamp having a heatable filament disposed adjacent said cell so that light emitted by the lamp energizes the said electrode of the cell, and means in said apparatus adapted to be connected to a source of alternating current for heating said cathodes and said lamp filament from said source.

3. In a signal receiving apparatus, an energizing circuit adapted to be connected to a source of alternating current, a plurality of electron discharge amplifying devices having their electron emitting elements energized through said circuit, a photoelectric detecting device having an electron emitting element and means for energizing said last named element through said circuit.

In testimony whereof I affix my signature.

ALEXANDER NYMAN.
